UNITED STATES PATENT OFFICE

2,645,402

COLLAPSIBLE CELLULAR CARTON

Kenneth T. Butterly, Kalamazoo, Mich., assignor
to Sutherland Paper Company, Kalamazoo,
Mich., a corporation of Michigan

Application February 12, 1951, Serial No. 210,605

3 Claims. (Cl. 229—28)

1

This invention relates to improvements in collapsible cellular cartons.

The main objects of this invention are:

First, to provide a cellular carton of the egg carton type which is strong and rigid when set up and at the same time may be transversely divided into sections, both sections having covers which are effectively retained in closed position.

Second, to provide a cellular carton of this type formed of an integral blank which may be shipped or stored in the flat and may be quickly and easily set up for use.

Third, to provide a cellular carton having these advantages in which the eggs in the sections are very effectively cushioned and protected.

Objects relating to details and economies of the invention will appear from the description to follow. The invention is pointed out in the claims.

A preferred embodiment of the invention is illustrated in the accompanying drawings, in which:

Fig. 1 is a perspective view of a carton embodying my invention in completely setup and closed form.

Fig. 2 is a fragmentary plan view with articles conventionally illustrated therein, one of the steps in severing the carton into sections being indicated by dotted lines.

Fig. 3 is an enlarged fragmentary view in longitudinal section on a line corresponding to line 3—3 of Fig. 2.

Fig. 4 is an enlarged fragmentary view on a line corresponding to line 4—4 of Fig. 5 with the transverse partitions in initial or unerected position.

Fig. 5 is a fragmentary longitudinal section on a line corresponding to line 5—5 of Figs. 4 and 6, the transverse partition members being shown in erected position by full lines and the outer and inner partition members being indicated by dotted lines in partially erected position.

Fig. 6 is an end elevational view of the erected carton, the expanded position of the parts being indicated by dotted lines.

Fig. 7 is an enlarged transverse section showing details of the features which permit expanding of the walls to accommodate large eggs.

Fig. 8 is a plan view of the blank in the flat.

I have illustrated and described my invention as embodied in an egg carton adapted to receive a dozen eggs and to be transversely separated or divided into two sections containing a half dozen eggs. In this preferred embodiment, the carton is formed of an integral blank shown in Fig. 8 and comprises a front wall 1, and rear wall 2, these walls constituting the side walls of the carton. The bottom members 3—3 are hingedly connected at 4 to the bottom edges of the side walls or the front and rear walls. The bottom members are hingedly connected to the longitudinal partition members 5—5.

The longitudinal partition members 5—5 are

2

hingedly connected to the bottom members 3 at 6—6. The bottom members have transverse slot-like openings 7—7 and 8—8, the openings 7 being at the ends of the carton and the openings 8 in spaced relation to the transverse center of the carton. The slots 7 have tongues 9 on their outer edges while the slots 8 have corresponding tongues 10 on their inner edges. The bottom has groups of crossing slits 11 intermediate the slots to provide cushioning elements.

When the blank is folded, the longitudinal partition members are disposed in side by side relation and adhesively secured together by strips of glue 12 as best shown in Figs. 6 and 7. One of the longitudinal partition members is provided with elongated slots 13, one for each cell, while the other longitudinal partition member is provided with C-shaped slits 14 providing tongues which are aligned with the slots 13 but are of such dimensions as to permit the tongues swinging through the slots when they are brought into registering position as shown in Fig. 5, the purpose of this being to provide some added space or clearance for larger eggs.

The top members designated generally by the numerals 15 are hingedly connected at 16 to the upper edges of the longitudinal partition members and at 17 to the glue or sealing strips 18. These sealing strips are joined in the blank by the fracturing line 19. The top members are slotted and scored to provide end transverse partition members 20 and intermediate transverse partition members 21. The pairs of partition members 20 and 21 swing oppositely in erecting and they lie oppositely in the blank as is shown in Fig. 8. The intermediate flap-like partition members 22 and 23 are cut from the top members between the pairs of partition members 20 and 21 and they also swing oppositely in erecting. The partition members 20 and 21 are hingedly connected to the top members at 25 while the partition members 22 and 23 are hingedly connected to the top members at 26.

The partition members 20 and 21 are provided with holes 27 in their swinging ends adapted to receive the tongues 9 and 10 on the edges of the slots 7 and 8 in the bottom members with the ends of the partition members 20 and 21 extending through the slots when the partition members are in fully erected position and engaging the tongues as is shown in Fig. 5. With the partition members 20 and 21 in erected position and in retaining engagement with the tongues 9 and 10, the outward swinging movement of the partition members from erected position is prevented, that is, swinging beyond their erected position. The blank has a central line of perforations 28 which extend from end to end thereof and centrally between the intermediate transverse partition members 21.

When the carton is fully erected, loaded, filled and closed as shown in Fig. 1, the carton may

be severed or broken along the weakened line 28 thereby providing in effect two cartons, six cells each. The cover 29 is provided with a closure flap 30 having a pair of facing closure tongues 31 on each side of the severing line 28. These closure tongues are beveled at 32 to facilitate their engagement with the hinge members 33 connecting the transverse partition members 22 and 23 to the top. Inasmuch as a facing pair of these tongues 31 are provided at each side of the severing line 28, each section of the severed carton is complete and provided with its individual cover so that each section or part of the severed carton is complete in itself including the cover.

The blank is folded so that the sealing flap 18, having adhesive designated at B, is adhesively secured to the side wall in an outwardly directed position as is shown in the drawing and constitutes a reinforcement therefor so the tongues of the flap cover may be easily engaged and disengaged. The sealing flap C is adhered to the rear flap 2 along the zone indicated at C.

The embodiment of my invention illustrated is adapted for expansion to accommodate large sized eggs, this expansion being illustrated by full and dotted lines in Figs. 6 and 7. To that end I provide a cut score 34 in the intermediate partition members in parallel spaced relation to the hinging scores 6 connecting the longitudinal partition members to the bottom members. The adhesive 12 is above these scores 34 so that the side walls may swing outwardly under pressure of larger eggs and the bottom portions 35 of the longitudinal partition members 5 below the scores 4 may swing outwardly and become in effect a part of the bottom, allowing the side walls to expand laterally as indicated by dotted lines in Fig. 6.

The carton of my invention as illustrated in the accompanying drawing may be formed of relatively light stock and at the same time is strong and rigid. The carton may be separated into two sections without materially sacrificing the protection of the contents or the substantial rigidity of the structure. The carton may be divided without opening the cover and, as stated, without any manipulation other than the matter of severing along the weakened line 28.

I have illustrated and described my invention in a highly practical embodiment thereof. I have not attempted to illustrate or describe other embodiments or adaptations which I contemplate as it is believed that this disclosure will enable those skilled in the art to embody or adapt my invention as may be desired.

Having thus described my invention, what I claim as new and desire to secure by Letters Patent is:

1. A collapsible carton formed of an integral blank and comprising front and rear side walls, bottom members hingedly joined to the lower edges of the side walls, longitudinal partition members hingedly joined to the inner edges of the bottom members and adhesively secured together in side by side relation, top members hingedly joined to the upper edges of the longitudinal partition members and to the inner sides of the side walls, said top members constituting cross members connecting the upper portions of the side walls with the said longitudinal partition members, the bottom members being outwardly inclined when the carton is erected, said top members being slitted and scored to provide transverse partition members

hingedly connected thereto, the longitudinal partition members having hinging scores therein disposed in spaced parallel relation to and above the said hinging connections for the bottom members to the longitudinal partition members, the lower adhesive connecting the longitudinal partition members being above the said hinging scores in said longitudinal partition members whereby the lower portions of the longitudinal partition members may swing outwardly to permit expansion of the side walls, and a cover hingedly connected to the upper edge of the rear side wall and provided with a closure flap on its swinging edge having tongues engageable with the top members adjacent the front wall.

2. A collapsible carton formed of an integral blank and comprising front and rear side walls, bottom members hingedly joined to the lower edges of the side walls, longitudinal partition members hingedly joined to the inner edges of the bottom members and adhesively secured together in side by side relation, and top members hingedly joined to the upper edges of the longitudinal partition members and to the inner sides of the side walls, said top members constituting cross members connecting the upper portions of the side walls with the said longitudinal partition members, the bottom members being outwardly inclined when the carton is erected, said top members being slitted and scored to provide transverse partition members hingedly connected thereto, the longitudinal partition members having hinging scores therein disposed in spaced parallel relation to and above the said hinging connections for the bottom members to the longitudinal partition members, the lower adhesive connecting the longitudinal partition members being above the said hinging scores in said longitudinal partition members whereby the lower portions of the longitudinal partition members may swing outwardly to permit expansion of the side walls.

3. A collapsible carton comprising front and rear side walls, bottom members hingedly joined to the lower edges of the side walls, longitudinal partition members hingedly joined to the inner edges of the bottom members and adhesively secured together in side by side relation, and top members having openings for receiving articles therethrough to be contained in the carton, said top member being hingedly joined to the upper edges of the longitudinal partition members and to the side walls, at least one of the longitudinal partition members having a hinging score therein in spaced parallel relation to and above the hinging connection of said partition member to the bottom member hingedly connected thereto, the lower adhesive connecting the longitudinal partition members being above said hinging score in said longitudinal partition member whereby the lower portion of said longitudinal partition member may swing outwardly to permit expansion of the side wall which is hingedly connected to the bottom member to which said longitudinal partition member is hingedly connected.

KENNETH T. BUTTERY.
